UNITED STATES PATENT OFFICE.

RODNEY L. HERRICK, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

SHOWCASE CONSTRUCTION.

Application filed January 17, 1923. Serial No. 613,171.

To all whom it may concern:

Be it known that I, RODNEY L. HERRICK, a citizen of the United States of America, residing at Grand Rapids, in the county of

5 Kent and State of Michigan, have invented certain new and useful Improvements in Showcase Constructions; and I do hereby declare the following to be a full, clear, and exact description of the invention, such as

10 will enable others skilled in the art to which it appertains to make and use the same.

The present invention relates to show cases and is more particularly concerned with a simple and novel form of connection

15 used in connecting together the front and end lights or glasses of the show case in constructions known as "all-glass" cases, said connections being used at the upper corners of the show case. This type of connection is not broadly new, but in my invention it is greatly simplified over what has heretofore been used, the number of parts reduced, one part taking the place of three, the connection can be applied to the front

20 glass of the show case at the factory so that no loose parts need be sent with the case to the place of installation, all parts being permanently attached in the factory thereby making the setting up and installation of

25 the case at its destination a very simple operation of which any ordinary mechanic is fully capable. At the same time a more economical construction from a manufacturing standpoint is provided and one that is stronger in service. It is simpler to add at the factory, is a better construction for shipment as the liability of glass breakage is reduced, no parts have to be applied to the end lights or glasses of the case so that in

30 a case where breakage does occur of said end lights they are easily obtained locally without the delay incident to reorder from the factory, and a stronger and more durable construction is produced. From the

35 combined advantages at the factory, in transit, for installation, and for service, the invention which I have made is designed, and it is its object and purpose to provide a connection which has these many advantages inherent in it, as will fully appear as understanding thereof is had from the following description of the invention taken in connection with the accompanying drawings illustrating the best form thereof, in which drawings,

Fig. 1 is a fragmentary perspective view of one end of a show case, the top glass being removed, and the connection of my invention being separated from the front glass.

Fig. 2 is a like view showing the said connection in place as used to connect the parts together.

Fig. 3 is a fragmentary perspective view of one end and the upper part of a front glass for a show case with the corner connection attached thereto as for shipment and with the tape forming a part thereof located above the upper edge of the glass.

Fig. 4 is an enlarged perspective view of 70 the corner connecting member, a part of the tape used therewith only being shown, and

Fig. 5 is a horizontal section at a corner of a show-case, the section being through the corner connecting member.

Like reference characters refer to like parts in the different figures of the drawings.

In the construction of the show case with which my invention is used, a back 1 is provided in which the doors for closing the case and by means of which access is gained to the case, are mounted (not shown), the back at each end and at its front side being formed with a vertical groove 2 for the reception of the rear edge of the end light 3 of plate glass, as shown. There are two of the end lights 3 and at the front of the case a front glass plate 4 is positioned vertically so as to come at its rear side against the front vertical edges of the end lights 3, as shown.

The connecting member which I have devised to be used at the upper front corners of the show case where the members 3 come against the front member 4 of the show case is made from sheet metal and comprises an upper side or top 5 with depending front and rear sides 6 and 7, one end being closed by an integral portion 8 of 100 metal. This member is adapted to be placed at the upper corner at each end of the front plate 4 of glass used in the show case construction and permanently secured thereto, suitable cement being used for this purpose 105 and when so attached, the upper side or top 5 comes against the upper edge of the glass, the depending sides 6 and 7 against the front and rear sides of the plate 4, respectively, and the end 8 against the vertical 110

end edge of the glass as shown. From the side 7 of the connecting member two tongues 9 and 10 are turned outwardly at right angles, being spaced apart a distance so that 5 the front edge of the end light 3 fits therebetween when the show case is assembled. Of course, a suitable channel member of metal may be soldered or otherwise permanently secured to the side 7 in place of the 10 tongues 9 and 10 as an exact equivalent.

At the upper side of the top 5, a member for engagement with the top plate of glass is located, the same comprising a horizontal leg 11, at one end turned upwardly at right 15 angles, as indicated at 12, and then turned back in parallel relation to the leg 11, thus terminating in an overhanging lip 13, the distance between the lip 13 and the leg 11 being equal to the thickness of the top plate 20 of glass to be used for the top of the show case. The leg 11 is connected to the upper side or top 5 of the connecting member by a rivet 14, an end of a length of metal tape 15 being secured by the same means, as 25 shown. This attachment of the leg 11 and tape 15 is a pivotal connection so that both may be turned about the vertical axis of the rivet 14 to occupy either the position shown in Fig. 3 where the tape and the leg 11 lie 30 above and in the same plane with the glass 4, or the position shown in Figs. 1 and 2 where they are located at right angles to the glass 4. In the former position, the front plate of glass 4 with the members attached 35 thereto at its upper corners may be readily crated and shipped all lying in the same plane. The free end of the tape 15 is turned back upon itself, as shown at 16, making a double thickness of metal through which 40 alined openings are made for the passage of a screw as will later appear.

The end lights or plates of glass are formed to required size and in my invention do not have to have any attachments whatever applied thereto. The connecting members used are attached to the front 4 only, it being obvious that no attachments need to be applied to the show case top plate any more than to the ends 3. In the assembly and installation of the case which is shipped in the knock-down, the back is positioned vertically, the rear edges of the ends 3 seated in the grooves 2 thereof and the front plate 4 positioned vertically at the front of the ends 45 3, the front edge portions of the ends 3 adjacent their upper ends being received between the tongues 9 and 10. The metal tape 15 is turned to lie at right angles to the front plate 4 and over the upper edge of the adjacent end 3, its double thickness end at 16 being received in a recess 17 cut in the upper edge of the back 1 adjacent its end, and a screw 18 passing through the openings in said part 16 to permanently secure the end 65 of the tape to the back. This draws the

front plate 4 into position against the front vertical edges of the ends 3, it being understood that the construction at each end of the show case is identical. The top plate of the show case may then be attached, the 70 front edge thereof passing under lips 13 and over the legs 11. Of course the usual felt strips are used between the contacting portions of the glass and over the strips or tapes 15 for appearance and to make the case 75 tight and dust proof, not being shown in the present construction as the same are old and well known.

The advantages in the factory in manufacturing of the invention are that for a 80 show case but two of the connecting members are required, one to be attached at each end of the front plate only of the case, the connecting member being a one-piece metal form readily made from a single piece of 85 sheet metal at a low cost and to which the metal tape 15 and the top glass holding clip are permanently and pivotally secured by a very simple operation. The end plates 3 need have no devices attached thereto. The 90 construction is very simple and inexpensive to make. For shipment, the elimination of any metal parts on the end plates reduces the danger of breakage. For installation, the fact that all parts which are to be used 95 are connected to the front plate and there has to be no fitting or connection of parts obviates the need of using labor skilled and familiar with show case work, as the installation with this construction is simple 100 enough that any one can do it, requiring no skill whatever. It is further evident that if glass is broken in transit, there is no need to await on the factory for new pieces except in the one instance where the breakage is of 105 the front plate, the end and top plates being supplied locally with a saving of time in getting the installation completed. Simplicity in manufacture, saving in expense in manufacture, shipping, from breakage 110 and time and expense in installation all follow from the present invention which is one of great practical merit. The invention is defined in the appended claims and it is to be considered that all forms of structure coming within the scope thereof are 115 comprehended by the invention.

I claim:

1. A device of the class described comprising a sheet metal construction having 120 two spaced apart sides, a top and an end, spaced apart tongues struck from one of said sides at right angles thereto, a member having a leg located against the upper side of the top and pivotally connected thereto to turn about a vertical axis, said leg at its free end being bent upwardly at right angles for a distance and then back over the leg and parallel thereto to terminate in a lip paralleling the leg, and a length 125 130

of metal tape attached to said member and said sheet metal construction and turning with the member about its pivotal connection to the said construction, substantially as and for the purposes described.

2. A device of the class described, comprising a member of metal adapted to embrace the corner of a rectangular piece of glass, means at one side of the member 10 projecting therefrom adapted to hold an edge of a second piece of glass located at right angles to the first piece, a second member pivotally mounted on the first member for engaging a third piece of glass 15 located in a plane at right angles to the planes of both the first and second pieces of glass, said second member being mounted to turn into the same plane with the first piece of glass or at right angles thereto, 20 and a length of metal tape attached to the second member in alinement therewith and moving with said second member, substantially as and for the purposes described.

3. A device of the character described, 25 comprising a single piece of metal formed to fit the upper corners of a vertical front plate of glass in a show case, means on the rear side of said member for engaging and holding the front edge portion of an end 30 plate of glass in the show case, a member pivotally connected to turn about a vertical axis on and with respect to said device and the front plate to which it is attached, said member being adapted to 35 engage with and hold a top plate to the show case, and an elongated strap connected with and movable with said member, being located in alinement therewith so as to be moved to a position directly over the upper 40 edge of the front plate or to a position at right angles thereto and directly over the upper edge of an end plate, said strap being designed to have attachment to the back of the show case, substantially as 45 and for the purposes described.

4. A device of the class described, comprising a single piece of metal having a top, two depending sides and a vertical end depending from the top and located 50 between the sides, the distance between the

sides and the width of the top and said end being substantially equal to the thickness of a plate of glass with which it is to be used, and vertical tongues projecting at right angles from one of said sides and spaced apart a distance substantially equal to the thickness of a plate of glass to be placed between the tongues, substantially as described.

5. A construction containing the elements 55 in combination defined in claim 4, combined with a member having one end formed to hook over an edge of a plate of glass, means for pivotally connecting said member to the top of said device, and an elongated 60 strap attached to the member in alinement therewith.

6. A show case front comprising a plate 65 of glass, a single metal member embracing the upper corners of the said glass and 70 having sides to bear against the front and rear sides of the glass, a top to bear against the upper edge and an end to bear against the end edges of the glass, spaced apart 75 tongues extending from the rear sides of the member, and an elongated metal strap pivotally connected at one end to the top of said member and adapted to turn with respect thereto about a vertical axis, substantially as described.

7. In a show case, a connecting means 80 for the front and end plates of glass therein, comprising a unitary device adapted to be attached to each end of the front plate and having means thereon to engage with 85 the adjacent end plate, and additional means for engagement with a top plate of glass in the show case, and means for connecting the said device with the back of the show case connected to the device, said 90 last named means and said additional means being movable together to two different positions, one a position for installation and connection of the last named means to the back, and the other to over the upper 95 edge of the front plate for shipment, substantially as described.

In testimony whereof I affix my signature.

RODNEY L. HERRICK.
